UNITED STATES PATENT OFFICE.

MAX VON RECKLINGHAUSEN, OF NEW YORK, N. Y., ASSIGNOR, BY MESNE ASSIGNMENTS, TO COOPER HEWITT ELECTRIC COMPANY, OF HOBOKEN, NEW JERSEY, A CORPORATION OF NEW JERSEY.

GAS OR VAPOR CONVERTER DEVICE.

1,110,573. Specification of Letters Patent. Patented Sept. 15, 1914.

Original application filed November 12, 1903, Serial No. 180,965. Divided and this application filed October 20, 1910. Serial No. 588,166.

To all whom it may concern:

Be it known that I, MAX VON RECKLINGHAUSEN, a subject of the Emperor of Germany, and resident of New York, county 5 of New York, State of New York, have invented certain new and useful Improvements in Gas or Vapor Converter Devices, of which the following is a specification.

When it is desired to construct and use 10 vapor converters such as are represented by the well-known mercury vapor apparatus of this class, it is often advantageous, especially when apparatus of large capacity is required to construct the devices mainly of 15 metal and to maintain electrodes within the devices, the negative electrode being as a rule in contact with the body of the container, and the positive electrode or electrodes being insulated by any suitable means 20 from the said body.

The problem of constructing efficient apparatus under these conditions involves questions of insulation and sealing and other similar matters all of which are highly im- 25 portant to the successful operation of the devices and to the maintaining of the requisite high vacuum inside the containing vessel. The question of short circuits also arises and means generally have to be provided 30 whereby such short circuits may be avoided.

The present invention relates to a novel form of apparatus of the general character set forth above, and its details will be fully described in the present specification and 35 illustrated in the accompanying drawings.

In the drawings, Figure 1 is a vertical section through my improved vapor converter, showing also a diagram of circuits which may be employed in connection there- 40 with; Figs. 2 and 3 are detail views showing different modes of securing an efficient seal for the apparatus; Fig. 4 is an enlarged detail view showing means for supporting and insulating one of the positive 45 electrodes of the apparatus and preventing short circuits; and Fig. 5 illustrates a modified construction for the same purposes.

Referring to the drawings, 1 is a vessel of metal, preferably steel or copper, and 2 is 50 a cap or cover of the same material as the vessel. At the bottom of the vessel 1 is formed a cup, 3, containing mercury, 4, constituting the negative electrode of the

apparatus. The mercury is in direct contact with the metal of the vessel 1, which may accordingly be itself considered a portion of the negative electrode.

As a means for securing a good seal as between the vessel and the cap or cover 2, I may provide the vessel with a shoulder, 5, and a flange, 6, and may, as illustrated in Fig. 3, press the cap upon the shoulder 5, so as to produce a ground joint, or I may interpose, as shown in Fig. 2, a strip or ring, 7, of asbestos or other suitable packing, pressure being applied in each instance to secure a good connection by means of clamps, 8, 8 secured by screw bolts, 9, 9. To complete the seal, I prefer to add mercury, as shown at 10, whereby a perfect seal is produced, 70 capable of sustaining with the containing vessel a very high vacuum.

In the present instance I have shown 2 positive electrodes, 11 and 12, and have illus- 25 trated more particularly in Figs. 4 and 5 means for supporting and insulating the said electrodes with respect to the cap or cover 2. In Fig. 5, for example, the electrode 12 is formed on or supported by a rod, 13, which is screw threaded at its top and connected 30 by such screw thread with a cone shaped metallic piece, 14, the latter is set into a tube, 15, of glass or other good insulating material, the same being shaped internally to receive and form a good joint with the me- 35 tallic piece 14 at a point substantially in line with the top of the cap or cover 2. Below the junction between the parts 14 and 15 the latter is formed into a tube of cylindrical shape surrounding the rod 13. In other 40 words, the tube 15 consists of two cylindrical portions of differing diameters connected by an inclined portion adapted to surround and fit the metal piece 14. The inclined portion of the tube 15 is itself surrounded by a screw 45 bushing, 16, capable of being screwed into the cap or cover 2, as shown.

Electrical connection with the positive side of the circuit is made through the mercury, 17, placed in the upper part of the 50 tube 15 and resting on the metallic piece 14. The mercury 17 serves not only as a circuit connection but also as a seal, as will be readily understood. I also place mercury 55 outside the tube 15 at the annulus where it is surrounded by the nut or washer, 16, and

I also apply mercury to the junction point between the flange 18, at the top of the said nut, and the cap or cover 2.

In Fig. 4 another mode of support and insulation for the positive electrode is shown. Here the cover 2 is provided with a cylinder, 19, which may be formed on said cover, and a tube 20, of glass or other good insulating material, passes down through this cylinder 10 and through the cover itself into the chamber of the container. The electrode 11 is mounted on a rod, 21, which is shouldered at 22 and screw threaded at the top to enter a metallic support, 23, within the tube 20.

15 The cylinder 19 has a screw thread connection with the nut 24 which immediately surrounds the tube 20. Between the walls of the tube 20 and the cylinder 19 on the outside is a packing of asbestos or similar material 20 and between the inner walls of the said tube and the rod 21 is a similar packing, the two packings being shown respectively at 25 and 26. By suitable adjustment of the packings 25 and 26, the tube 20 may 25 be firmly held in position while by means of mercury seals, 27, 28 and 29 all leakage of air into the containing vessel will be avoided.

It is found in operating devices of this class, particularly where the vacuum is for 30 any reason imperfect, that the film of mercury is liable to be formed on the insulating tube which surrounds the positive electrode supports and that this film if carried far enough may cause a short-circuit between 35 the positive and negative electrodes. To avoid this I may arrange the positive electrode as indicated in Fig. 5 where it is formed into an upright cup on the lower end of the rod 13 and located so as to surround the lower end of the insulating tube 15. Owing to the great heat which is developed at the positive electrode, the lower end of the tube 15 will be so highly heated by the radiation or convection from the electrode 12 that no condensation of mercury 45 will take place at that part of the tube. Consequently there will be no opportunity for the short circuit under such conditions.

I have indicated at 30 a film of mercury 50 due to condensation as described, showing, however, the lower end of the tube 15 free from such a film.

Another mode of preventing the film from causing a short-circuit is indicated in Fig. 4 55 where the tube 20 is made to project so far above the electrode 11 that it leaves a space toward the top of the tube which is too remote for the deposition of mercury to take place. In other words, the mercury of condensation is all deposited on the inner walls 60 of the tube before it reaches a point where it might cause or come into contact with the rod 21, even though such rod might touch the tube near its upper end.

65 A further danger which is to be guarded

against in the operation of these vapor converters is due to the development at the negative electrode of what is known as negative electrode flame. There appears to be a tendency for such a flame to attach itself to the solid portions surrounding the negative electrode, and this leads to a disintegration of the surrounding portion in case it is formed of metal. By introducing into the cup containing the mercury constituting the negative electrode, a ring of porcelain or the like, as shown at 31, and by starting the flame inside the said ring, the flame can be prevented from attacking the metal and the difficulty mentioned above can be avoided.

To insure the proper starting of the device into operation, I may pass through the cap 2 a glass or porcelain tube, 32, a suitable packing box being provided for insuring a good seal. This packing box may be similar 85 to either of those already described in connection with the insulating tubes surrounding the positive electrode leads. Into the tube 32 I may insert a wire, 33, and cause its lower end to impinge against the inner wall 90 of the tube at or near the surface of the mercury electrode 4. The wire may be connected in any suitable manner with the positive side of the circuit, when it forms what may be called an internal starting 95 band, acting on the same principle as the well known external starting band.

For the sake of clearness I have shown a direct current generator, 34, having one pole connected to the negative electrode 4 and the opposite pole connected to the positive electrodes 11 and 12 and also to the wire 33. In the circuit is included an inductance device, 35, and a snap or quick-break switch, 36, is connected in a shunt circuit around 100 the said inductance device. I may include a resistance, 37, in this shunt circuit. The action of starting the converter is now well-known, but I may say that on operating the switch, 36, whose terminals are usually 105 placed under oil, the shunt circuit is broken, the energy stored in the inductance 35 is discharged through the converter, thereby starting the apparatus into operation. The operation continues by virtue of the current 110 from the generator 34.

I have mentioned asbestos as a suitable material for the packing illustrated at 25 and 26, but owing to the fact that the presence of carbon in a converter of this kind 120 is injurious, I prefer that asbestos, if used, should first have its rubber binder burnt out, thus removing the carbon. In general, I do not wish to confine myself to the use of asbestos, and may use any material which 125 is in such mechanical condition that it can be used as a packing, preferably, however, non-carboniferous material. I may indeed use packings in powdered form, such as powdered magnesia or the like. It is only 130

necessary, besides the other conditions mentioned, that the material used as the packing should be flexible and compressible, preferably without carbon in it or associated 5 with it.

This application is a division of my application Serial Number 180,965, filed November 12, 1903.

I claim as my invention—

- 10 1. A vapor electric apparatus comprising a metal container, a mercury cathode therein and an insulating shield separating the operating portion of the surface of said electrode from said container.
- 15 2. A mercury vapor apparatus comprising an exhausted container of metal and a cathode therein, together with means for preventing the negative spot from reaching the surface of the container.
- 20 3. A vapor electric apparatus comprising

an exhausted container, a cathode therein, an insulating ring surrounding a portion of the surface of the said cathode and extending above said cathode, together with means for exciting said cathode at the portion of its surface lying within said ring. 25

4. A vapor electric apparatus comprising an exhausted container of metal, an electrode of liquid material capable of wetting to some degree the surface of said container 30 and means for restraining the operating current at the surface of the said electrode from reaching the wall of said container.

Signed at Paris, France, this sixth day of October, A. D. 1910.

MAX VON RECKLINGHAUSEN.
